UNITED STATES PATENT OFFICE

2,507,994

STARTING APPARATUS FOR RACE TRACKS

Howard A. Pierce, Hamburg, N. Y.

Application May 22, 1947, Serial No. 749,795

2 Claims. (Cl. 119—15.5)

1

This invention relates generally to a race-starting apparatus but more particularly to a race-starting device designed for use for harness or sulky racing.

It has for one of its objects to provide an apparatus of this character which is so designed and constructed as to insure proper, even and uniform starting of such races, and which is accomplished in such a manner as to keep the race-way free and clear of objectionable obstructions which might result in injury to the horses or to their drivers, as well as not to interfere with or distract the attention of the horses.

Another object of the invention is to provide a sulky race starting apparatus which is adapted to be installed along the track or race-way so as not to obstruct the view of those attending such races and which will effectually prevent the delays and other objections now encountered in the starting of sulky or so-called harness races.

A further object is to provide a simple, compact and reliable starting apparatus for sulky racing which is electrically controlled and positive in operation, and which can be governed remotely from a single control tower or station along the track.

Other features of the invention reside in the construction and arrangement of parts herein-after described and particularly pointed out in the appended claims:

In the accompanying drawings:

Figure 1 is a perspective view of the starting apparatus embodying my invention. Figure 2 is a fragmentary top plan view thereof showing one of the carriages, with the enclosing body removed, and associated parts. Figure 3 is a fragmentary side view thereof. Figure 4 is a cross section taken on line 4—4, Figure 2. Figure 5 is a fragmentary perspective view of one of the carriages showing the manner of supporting the barrier tape thereon.

Similar characters of reference indicate corresponding parts throughout the several views.

Referring now to the drawings, wherein I have shown the preferred embodiment of my invention, 10 indicates that portion or stretch of the track or race-way along which the races are started, 11 and 12 indicate inner and outer fences paralleling the race-way, and 13 indicates a pair of sulkies preparing for a start. Disposed in the space between the parallel fences for movement along the starting stretch of the race-way, and operating at a level substantially within the height of the fences so as not to interfere with the patron's visibility in observing the races or distracting

the attention of the horses, is my starting apparatus which consists generally of stream-lined carriages 14, 14 individually powered to travel in unison forwardly and backwardly along the starting stretch and having a vertically-displaceable barrier 15 supported therebetween and extending transversely of the race-way. This barrier, during the starting of the race, assumes the lowered position shown in Figures 1 and 5, and when all horses in the race are abreast transversely aligned with the barrier, it is smartly elevated to clear the horses and permit the race to proceed. A control tower 16, manned by one operator, is stationed at an appropriate place along the starting stretch of the track for electrically governing by remote control the movement of the carriages and the actuation of the barrier.

The carriages and their mounting structure are identical in construction and a description of one will suffice for both. Each carriage consists of a suitable frame or chassis 17 having front and rear, longitudinally-aligned rollers or wheels 18 which engage the top face of a single ground track or monorail 19 paralleling the starting stretch of the race-way adjacent the inner fence 11, and companion transversely-aligned guide rollers 20 which engage the opposite sides of the rail-head in the manner shown in Figures 3 and 4. At the upper end of its outer side the chassis has front and rear bearing blocks 21 in which longitudinally-aligned rollers or wheels 22 and transversely-aligned rollers 23 are journaled, and which engage, respectively, the lower face and opposite sides of an elevated guide rail 24 paralleling the ground rail 19 and adjustably supported on posts 25 disposed inside and below the level of the outer face 12. By this construction, the carriages are guided smoothly in a straight path and they are effectually held against both vertical and lateral displacement.

Disposed between the outer side of each carriage and the elevated guide rail 24 and below the plane of the latter are a plurality of horizontal conductor bars or members 26 which are adapted to be connected to a source of power and which are supported on posts 27. Mounted on and projecting from the adjoining side of the carriage are contact rollers or trolleys 28 by which electrical current is supplied to operate the carriages and the displaceable barrier 15.

Motion is transmitted to each carriage 14 to propel it in a forward and reverse direction by an electric motor 29 mounted at one end of the chassis 17 and having its upright shaft 30 connected by a drive pinion 31 with a gear rack

32 applied to the web portion of the companion ground rail 19. This drive motor is preferably of the shunt wound type for quick starting and stopping intermittent duty, and embodies therein the usual type of dynamic braking, so that when the race is to be started and the barrier 15 is to be raised, the carriages can be brought to a comparatively quick stop.

The displacement of the barrier is also electrically controlled and for this purpose an electric motor 33 of like type is employed for effecting its prompt raising clear of the race-way when the race is to be started. This barrier is preferably in the form of a flexible tape 34 detachably connected at its ends to crank arms 35 projecting forwardly or lengthwise from the opposing inner sides of the carriages to swing vertically. Each crank arm is connected to a transverse shaft 36 journaled in the companion carriage-chassis 17 and driven from the motor 33 in any suitable manner, as for example, by a worm 37 on the motor-shaft and a worm wheel 38 on said transverse shaft. As shown in Figures 1 and 4, each arm 35 terminates at its free end in a laterally-offset portion 39 which overhangs the top of the inner fence 11 and a depending portion 40 disposed just inside the fence and to which the ends of the barrier tape are connected. The lower ends of the arm-portions 40 terminate substantially flush with the top of the fence 11, whereby there are no parts of the apparatus which objectionably protrude into the race-way area to cause accidents or distract the attention of the horses or interfere with the vision of the spectators.

The carriage drive and barrier actuating motors 29 and 33, respectively, are governed by one operator in a remote fashion from the control tower 16 which is equipped with the necessary control switches (not shown) for governing the motors to regulate the speed of the carriages with that of the horses and also to elevate the barrier 15 at such time as the horses are abreast of one another.

While manifestly simple and compact in construction, this apparatus is so designed that it can be readily installed, it is positive and reliable in operation, and it assures the proper starting of the races to the satisfaction of the drivers as well as the spectators. Furthermore, it requires but one operator to control it and all its parts, with the exception of the necessary flexible barrier tape 34, are located beyond the area of the race-way and below the level of the fences so as not to interfere in any way with the travel of the horses and sulkies along the race-way or obstruct the vision of the spectators.

I claim as my invention:

1. A race starting apparatus of the character

described, comprising single, ground-engaging track rails disposed at opposite sides of the race-way along the starting path thereof, elevated guide tracks paralleling said track rails in spaced relation thereto, companion carriages having upper and lower portions adapted to be propelled along said rails and each having sets of guide rollers at its lower and upper portions for opposing vertical and lateral engagement with the companion track rails and guide tracks, respectively, a vertically-displaceable barrier member mounted on said carriages and extending transversely of the race-way, motors applied to said carriages for propelling them in unison along the race-way and for actuating said barrier member to and from its operative position, conductors adapted for connection to a source of power disposed parallel to the track rails, and trolleys in circuit with said motors and mounted on said carriages for engagement with said companion conductors.

2. A race starting apparatus of the character described, comprising single, ground-engaging track rails disposed at opposite sides of the race-way along the starting path thereof, elevated guide tracks paralleling said track rails in outwardly-spaced relation thereto, companion carriages having upper and lower portions movable along said rails and each having sets of guide rollers at its lower and upper portions for opposing vertical and lateral engagement with the companion track rails and guide tracks, respectively, means for propelling said carriages in unison along the track rails, companion vertically-swinging crank arms applied to the carriages at those sides thereof facing the race-way, a flexible barrier tape extending transversely of the race-way and connected at its ends to said crank arms, and means operatively connected to said crank arms to raise and lower the same to bring the barrier tape into and out of its operative position.

HOWARD A. PIERCE.
